PACKAGING OR CRATING STRUCTURE

Filed Sept. 17, 1931

UNITED STATES PATENT OFFICE

HARRY C. WAY, OF WHEELING, WEST VIRGINIA

PACKAGING OR CRATING STRUCTURE

Application filed September 17, 1931. Serial No. 563,370.

My present invention relates to improvements in packaging or crating structures of the general character constituting the subject matter of my prior applications, Serial 5 Numbers 520,395 and 558,120 and my present purpose, generally speaking, is to provide a packaging or crating structure which embodies the fundamental desirable features of my prior structures referred to, and which 10 further embodies other features of advantage both from a production and utilitarian standpoint.

Heretofore, in the packing or crating of articles, particularly flat steel plates which 15 may be coated with tin or other substance to prevent corrosion, it has generally been the practice to pack such plates face to face. In transporting such packages, due to the rough handling and the vibration to which the package 20 may become subject as in the case of railway transportation, the plates have a tendency to rub, one against the other. Since there is always a certain amount of dust and sometimes steel particles upon the surface of the plates from the atmosphere and handling at the factory, this dust and particles will 25 rub against the surface of the plates due to the shifting of each plate relative to its neighbor and will rub holes and scratch the surface of the plates, oftentimes through to the basic steel surface.

The present invention seeks to overcome the above tendency of the plates to shift by the provision of a rigid and substantial package which is adjustable to the exact size of the plates crated or packed and prevents their consequent shifting due to the handling of the packages. A crating structure of such a type comprises generally side and end elements of L-shaped cross section which are of sufficient length to extend substantially but not fully the length and width of the package of plates or other articles along the corners thereof. At the points of intersection of the side and end elements, corner elements of substantially L-shape and L-shaped cross section are provided which embrace the end portions of the side and end elements.

50 In the preferred embodiment of my inven-

tion, the end portions of the side and end elements are provided with slots which register with complementary slots formed in the adjacent portions of the corner elements. Securing elements such as bolts or the like 55 are passed through the slots in the end and side elements and through the slots in the corner elements, thus permitting the corner elements to slidably interlock or engage with the side and end elements and allow adjustment therebetween to accommodate plates of varying size and to permit the package, after having once been formed, to be drawn tightly around the contained articles thus eliminating any possibility of their shifting during transit.

Each corner element at its innermost edge preferably is formed with an arrowhead projection or a perforation through which is passed a securing member or brace such as 70 a wire, metal strip or the like. This member is then passed to and connected with a corner element diagonally located with respect to the first element and on the opposite side of the package. Thus a series of reinforcing members are formed on each side of the package, crossing one another at approximately the center of each side. These members are designed so that they may be tightened to any desired degree, thus imparting 75 to the package the requisite degree of rigidity and strength to withstand any rough handling to which it may thereafter become subject.

In a modification of my invention, the reinforcing or tightening members may be eliminated and the bottom of the package made of reduced size relative to the top so that the bottom may nest therein. This arrangement affords a sturdy rugged structure 90 which may be bound together and fastened by one or more metal strips or the like passed therearound and tightened to the desired degree.

With the foregoing and other objects in view, which will become more fully apparent as the nature of the invention is better understood, the same consists in the novel features of construction, combination and arrangement of parts as will be hereinafter more 100

fully described, illustrated in the accompanying drawing and defined in the appended claims.

In the drawing wherein like characters of reference denote corresponding parts in the different views:—

Figure 1 represents an asymmetric view of a crating element;

Figure 2 represents a more detailed view of one of the side and corner elements illustrating particularly the slots formed in each whereby adjustability of the two elements relative to each other is secured;

Figure 3 is a detailed view of the elements of Figure 2 in engaged relation;

Figure 4 is a view of a modification of the corner element of Figure 2;

Figure 5 is an asymmetric view of a modified form of my crating structure wherein the side reinforcing elements are eliminated and the bottom of the crate nested within the top;

Figure 6 is a detailed view of the crate of Figure 5 showing the elements in separated relation;

Figure 7 illustrates the manner in which the side and end elements of the bottom of the crate of Figure 5 are fastened to the corner elements to permit of nesting within the top of the crate; and

Figure 8 is a detailed view of the elements of Figure 7 in engaged relation.

With reference to the drawing and particularly to the construction shown in Figure 1, it will be observed that my crating or packaging structure comprises essentially two pair of side crating elements designated as 11, two pair of end crating elements designated as 12, two pair of upright elements designated as 13 and eight corner elements 14 employed to connect the side, end and upright elements together.

The side, end and upright crating elements may be of different lengths, but in other respects they are duplicates of one another, each being of angle or L-shaped cross section and comprising two side walls 15 and 16, preferably located at right angles to one another. They are formed preferably from sheet metal by a rolling or pressing process or in any other suitable manner, and while they may be formed individually, it is preferred to roll, press or otherwise form a blank of elongated form and to thereafter cut this blank into sections of the desired length to constitute such elements.

Preferably the flanges of each end, side and upright element are mitered at their ends to permit a rectangular assembly of said elements with the ends of the side walls 15 and 16 of the respective side, end and upright elements disposed in substantially abutting relation, and in accordance with the embodiment of the invention illustrated in Figures 1 to 4, the side wall 16 of each side and end element is provided with a slot 17 to permit

of an adjustment which will be hereinafter described.

The corner elements 14 like the side and end elements are formed in angular or L-shaped cross section and are duplicates of one another, each being of substantially angular or L-shape whereby the right angularly disposed legs or arms thereof are adapted for cooperation with the adjacent end portions of one of the side and one of the end elements, respectively, and like the side and end elements may be formed either individually or by cutting an elongated blank into sections of desired length.

Each corner element initially is straight and composed in cross section of a side wall 18 and a lateral flange 19, V-shaped notches being formed in the side wall 18, medially thereof, whereby the element is adapted to be bent into its angular or L-shape aforementioned.

The sectional size of the corner elements is slightly greater than the sectional size of the side and end elements whereby the legs or arms of the corner elements are adapted to snugly receive and embrace the end portions of the side, end and upright elements.

In the lateral flanges 19 of each corner element is formed a slot 21, preferably parallel and arranged in complementary relation to the slot 17 of element 11. In addition to the slot 21, an arrowhead projection or abutment 22 is formed adjacent the outside lower corner of each lateral flange 19 for a purpose to be later described.

Between the upright, side and end elements and held in fixed relation thereby, flat elements 23 formed of metal, fibre, cardboard or the like may be employed to further protect the contents of the package.

To effect packaging or crating of articles by means of the elements described, a pair of side elements 11, a pair of end elements 12 and two pair of upright elements 13 are placed in position as shown in Figure 1 and the lower corner elements 14 applied thereto and secured loosely to the side and end elements by means of bolts and nuts 24 inserted into the complementary slots 17 and 21 of elements 11 and 14, respectively. Bolts 24 are preferably countersunk to permit of a smooth surface within the interior of the crate.

The articles to be packed such as steel plates are placed in the crate thus formed and a flat element 23 applied to the top thereof, side and end elements 11 and 12 being applied in a manner similar to the formation of the bottom of the crate. Corner elements 14 are applied to the side and end elements 11 and 12 and fastened thereto by securing means 24. The corner elements 14 are forced inwardly bringing the flat elements 23 into abutting relation with the packed articles. It will be noted that the side elements 11, the end elements 12 and the upright elements 13 are suf-

ficiently short of the ends of the package so as to permit of inward movement of the corners 14. The bolts 24 acting in conjunction with the slots 17 and 21 serve to lock the corner elements 14 in position when they have been forced inwardly as far as is desired.

Brace members 25 consisting of metal strips or wires are placed over the arrowhead projections or abutments 22 of the corners 14 and are so arranged as shown in Figure 1, that diagonally opposite corner elements on each side of the crate are connected. The braces 25 may then be tightened by twisting or other suitable operation, pulling each corner element 14 inwardly on a line toward the center of the crate, thus providing a rigid and secure structure.

The arrowhead projections 22 may be substituted for by the projections 26 provided with perforations 27 (as shown in Figure 4) through which the brace members 25 may be passed. Either the arrowhead projection 22 or the perforation 27 with its projection 26 may be easily stamped or punched from the sheet metal with very little trouble.

From the above description, it is apparent that according to this preferred embodiment of the invention, a rugged and secure package is obtained. The corner elements are readily removable to facilitate the opening of the package or crate and the several elements comprising the package are readily capable of repeated use. By reason of the novel form of securing devices, the crate is readily adjustable in both width and length. Moreover, according to the invention as described it is also apparent that only a minimum amount of metal is required for the complete structure; that the corners of the structure are effectively reinforced by the corner elements, and that the production of the side and end elements is greatly simplified due to the similarity in structure therebetween.

With reference to the modification illustrated in Figures 5 and 6, a crate or package similar to the crate or package of Figure 1 is shown with the exception that the upright elements 13 are eliminated and the crate formed of a top unit 28 and a bottom unit 29, the latter being of reduced size so as to permit of its nesting within the top unit.

The unit 28 is formed in a manner similar to the top and bottom of the crate of Figure 1 i. e. side elements 11 and end elements 12, preferably of L-shaped cross section engage a flat element 23 and are held in position by corner elements 14 through complementary slots 17 of side and end elements 11 and 12 and slots 21 of the corner elements 14, thus permitting adjustment of the crate in both length and width.

The unit 29 or the bottom unit is formed of side elements 31 and end elements 32, preferably of L-shaped cross section. Side walls 33 of each side and end element are provided

with a plurality of slits near each end thereof to provide any desired number of tongues 34 spaced equidistantly apart longitudinally of said walls. In the side walls 35 of each corner element is formed a series of narrow slots 36 which are evenly spaced longitudinally of said wall the same amount as the spacing of the tongues 34 for the selective reception of said tongues.

To assemble the unit 29 which forms the bottom of the crate, the tongues 34 of the side and end elements are first bent over to extend outwardly from said elements. The side elements are then disposed in embracing relation to the sides of the articles to be packed, the end elements are disposed in embracing relation to the ends of the articles, and the corner elements are disposed with their leg or arm portions in embracing relation to the end portions of the side and end elements, respectively, with the tongues 34 of the side and end elements extending through the slots 36 of the adjacent legs of the corner elements. The tongues are then bent inwardly against the outer faces of the side walls of the corner elements whereby the side, end and corner elements are locked together in collective embracing relation to the marginal portions of the articles packed.

The top unit 28 is then placed over the bottom unit 29 with its contained articles and the two units suitably secured together in rigid relation preferably by a wire or metal member or members 37 passing around the two units as shown in Figure 5.

Obviously, by reason of the modifications of my invention as shown, a great saving in material may be effected over the use of prior crating devices particularly in instances where the package or crate is of material thickness. Moreover, it is apparent that as equivalents, substantially of the L-shaped crating sections, top and bottom plates may be provided to extend completely across the top and bottom of the package and marginal flanges may be provided on said plates to overlie the edges of the package and to be fastened to the corner elements in either of the different ways shown and described. It will be noted also that the several elements composing the crate or package are readily capable of repeated use, thus effecting material economies in the handling and packing of the articles.

The bolts 24 employed in conjunction with the complementary slots of the side, end and corner elements may be omitted if desired, the brace members 25 in such a case, connecting the diagonally opposite corner elements serving to hold the package securely and rigidly.

From the foregoing description considered in connection with the drawing, it is believed that the construction, mode of assembly and the advantages of my present packaging or

crating structure will be clearly understood. It is desired to point out, however, that while certain specific embodiments have been illustrated and described herein, the same is capable of embodiment in specifically different mechanical structures within the spirit and scope of the invention as defined in the appended claims.

I claim:

- 10 1. A structure designed and proportioned for packaging or crating rectangular sheets of metal comprising rigid longitudinal elements of L-shaped cross section shorter than the length of the sheets to embrace longitudinally extending corners of the sheets, rigid transverse elements of L-shaped cross section shorter than the width of the sheets to embrace transversely extending corners of the sheets, rigid corner elements slidably embracing the aforesaid longitudinal and transverse elements in such manner that by relative inward movement of adjacent corner elements the said longitudinal and transverse elements are caused to exert pressure tightly against the sheets, and means for holding said corner elements tightly embracing said longitudinal and transverse elements thereby to cause the latter elements to hold the sheets firmly against movement relative to each other.

30 2. A structure designed and proportioned for packaging or crating rectangular sheets of metal comprising rigid longitudinal elements of L-shaped cross section shorter than the length of the sheets to embrace longitudinally extending corners of the sheets, rigid transverse elements of L-shaped cross section shorter than the width of the sheets to embrace transversely extending corners of the sheets, rigid L-shaped corner elements of L-shaped cross section slidably embracing the aforesaid longitudinal and transverse elements whereby relative inward movement of all of the corner elements causes the longitudinal and transverse elements to exert pressure tightly against the sheets, and tension elements to connect diagonally opposite corner elements to hold said corner elements tightly embracing the longitudinal and transverse elements thereby to cause the latter elements to hold the sheets firmly against movement relative to each other.

50 3. A structure designed and proportioned for packaging or crating rectangular sheets of metal comprising rigid longitudinal elements of L-shaped cross section shorter than the length of the sheets to embrace longitudinally extending corners of the sheets, rigid transverse elements of L-shaped cross section shorter than the width of the sheets to embrace transversely extending corners of the sheets, rigid L-shaped corner elements of L-shaped cross section slidably embracing the aforesaid longitudinal and transverse elements whereby relative inward movement of all of the corner elements causes the longitudinal

dinal and transverse elements to exert pressure tightly against the sheets, each of said longitudinal, transverse and corner elements being inclusive of a vertical and a horizontal flange and the inner face of each flange of each of said elements being continuously flat thereby to avoid any inwardly directed projections which might mar the sheets, and tension elements to connect diagonally opposite corner elements to hold said corner elements tightly embracing the longitudinal and transverse elements thereby to cause the latter elements to hold the sheets firmly against movement relative to each other.

4. A structure for packaging or crating 80
metal sheets as set forth in claim 1 in which
rigid vertical elements of L-shaped cross sec-
tion and of less height than the sheets are
provided to embrace the vertically extending
corners of the sheets. 85

5. A structure for packaging or crating metal sheets as set forth in claim 2 in which rigid vertical elements of L-shaped cross section and of less height than the sheets are provided to embrace the vertically extending 90 corners of the sheets.

6. A structure for packaging or crating metal sheets as set forth in claim 3 in which rigid vertical elements of L-shaped cross section and of less height than the sheets are provided to embrace the vertically extending corners of the sheets. 95

7. A package of rectangular sheets of metal comprising rigid longitudinal elements of L-shaped cross section shorter than the length of the sheets embracing longitudinally extending corners of the sheets, rigid transverse elements of L-shaped cross section shorter than the width of the sheets embracing transversely extending corners of the sheets, rigid L-shaped corner elements of L-shaped cross section slidably embracing the longitudinally and transversely extending elements whereby relative inward movement of all of the corner elements causes said longitudinal and transverse elements to exert pressure tightly against the sheets, and tension elements connecting diagonally opposite corner elements and holding said corner elements tightly embracing the longitudinal and transverse elements whereby the latter elements are caused to hold the sheets firmly against movement relative to each other. 100 105 110 115

8. A package of metal sheets as set forth in claim 7 in which rigid vertical elements of L-shaped cross section shorter than the height of the sheets embrace the corners of the sheets and are embraced at their ends by said corner elements. 120

9. A package of rectangular sheets of metal comprising rigid longitudinal elements of L-shaped cross section shorter than the length of the sheets embracing longitudinally extending corners of the sheets, rigid transverse elements of L-shaped cross section shorter 130

than the width of the sheets embracing transversely extending corners of the sheets, rigid L-shaped corner elements of L-shaped cross section slidably embracing the longitudinally 5 and transversely extending elements whereby relative inward movement of all of the corner elements causes said longitudinal and transverse elements to exert pressure tightly against the sheets, each of said longitudinal, 10 transverse and corner elements being inclusive of vertical and horizontal flanges and the inner face of each flange of each of said elements being continuously flat thereby to avoid any inwardly directed projections 15 which might mar the sheets, and tension elements connecting diagonally opposite corner elements and holding said corner elements tightly embracing the longitudinal and transverse elements whereby the latter elements 20 are caused to hold the sheets firmly against movement relative to each other.

10. A package of metal sheets as set forth in claim 9 in which rigid vertical elements of L-shaped cross section shorter than the 25 height of the sheets embrace the corners of the sheets and are embraced at their ends by said corner elements.

In testimony whereof I hereunto affix my signature.
